CLAIM

The ornamental design for a multilamp flashlamp article having combustible member therein, as shown and described.

DESCRIPTION

FIG. 1 is an isometric view of a multilamp flashlamp article having combustible member therein showing our new design;

FIG. 2 is a side elevational view thereof, shown on a slightly smaller scale;

FIG. 3 is a top plan view thereof, shown on a slightly smaller scale;

FIG. 4 is a bottom plan view thereof, shown on a slightly smaller scale.

The broken line disclosure of the mounting post as shown in FIGS. 2 and 4 is for illustrative purposes only and forms no part of the claimed design.
